HAIR CURLER

Jack Ashford, Jackson Heights, N. Y.

Application March 9, 1945, Serial No. 581,786

2 Claims. (Cl. 132—42)

1

This invention relates to hair curlers, and more particularly to curlers of the type adapted to form a curl by winding of a strand of hair therearound and permitting the curling device to remain in place, with the hair curled thereon, for a period of time to effect setting of the hair in curled formation.

Curlers of this general class have heretofore been produced in a wide variety of forms and constructions, and are adapted to be used by individuals personally, or commercially by beauty parlor operators in producing curls. In using curlers of this type it is preferable to also moisten the strand of hair with suitable liquids for assisting in forming the curl, and/or causing the curl to become set. Such curlers may be used by beauty operators either with or without heat, and may also be employed in forming curls by what is now known as a "cold" permanent waving process. Such curlers, due to their peculiarities of construction, all necessitate partial or complete uncurling of the formed curls in the process of removing the curlers from the hair. This practice tends to destroy to a large extent the permanency of the curl thus formed, and results in greatly increasing the size thereof. Furthermore, such curlers due to their construction and manner of use require a substantial amount of time in effecting their removal from the curled strand of hair, and necessitate fingering of the curl formed by the curlers in an attempt to restore the curl to a proper curled formation. By such procedure it is a practical impossibility to obtain a finished curl which is relatively set in form and of a size approximating the size of the curl when initially wound on the curler.

One of the objects of this invention is to provide an improved curler of the character indicated which is constructed and arranged so as to permit quick and easy removal thereof from the curl of hair formed thereon, without necessitating unwinding of the curl.

Another object is to provide an improved curler of the character described which is constructed and arranged so as to permit obtaining finished curls of substantially the same size as when the hair is wound in curled formation around the curler.

A further object is to provide an improved curler of the character indicated, having a main body portion formed of two detachably connectible members, constructed and arranged so as to be quickly and easily removed from the curl of hair formed around the body without necessitating unwinding of the curl.

Still another object is to provide an improved curler of the character indicated wherein the main body portion, about which the strand of hair is wound in curled formation, comprises two detachably connectible members and wherein one of the members may be quickly and easily separated from the other while the curl of hair remains in curled form around the other so as to permit the remaining member to be reversely rotated in uncurling direction so as to produce a curl of a size larger than that initially formed when wound around the body of the curler.

Other objects and advantages of the curler embodying the present invention will be apparent from the following description, taken in connection with the accompanying drawing in which:

Figure 1 is a diagrammatic view of the human head showing the curler embodying the present invention positioned with respect to a strand of hair, preparatory to winding the hair therearound for forming a curl.

Figure 2 is a perspective view of the curler embodying the present invention, shown in assembled relation.

Figures 3 and 4 are perspective views of the two cooperating detachably connectible members constituting the main body of the curler.

Figure 5 is a perspective view of the holding clip adapted to be associated with one of the body members.

Figure 6 is a perspective view of the retaining member associated with the main body of the curler for releasably maintaining the strand of hair in curled form on the curler body.

As above stated, the curler embodying the present invention is capable of use by individuals for personal hair curling, and are also adapted for convenient practical use by beauty parlor operators in the process of forming curls. In either case it is preferable that a plurality of the curlers be utilized to form curls around different portions of the head, and the curlers are permitted to remain in place for a period of time in order to effect proper setting of the hair in curled formation. When the devices are used by beauty parlor operators, a plurality of the curlers are positioned at the desired places on the head at which the curls are to be formed, and then if desired the "cold" wave process may be applied, or the heat process may be employed, after which the curlers may be quickly and easily removed as will hereinafter be described, leaving the curls in substantially the same size and preset condition as assumed when wound on the curlers.

50

55

The curler embodying the present invention includes a main body portion indicated generally at A, of generally elongated formation, composed of two separate members indicated at 10 and 11, constructed and arranged so as to be detachably connected together in axial relation. In the construction as illustrated, the outer end of the body member 11 is formed with a button shaped undercut head 14, and the opposite end of said member terminates in an extension or stem portion 15, of relatively small diameter and of substantially cylindrical form, adapted to be telescoped into an opening 16 extending axially throughout the entire length of the other body member 10 when said body members are assembled in operative relation.

The outer or lateral surfaces of the two members 10 and 11, constituting the main body when assembled, are formed so that the main intermediate portion thereof is of gradually reducing cross section as it approaches the middle of the length thereof, so that the cooperating outer surfaces of the two members 10 and 11, individually are of substantially frusto conical formation. This construction in effect constitutes a trough and tends to direct and confine a strand of hair in position when wound around said body. It will be observed that when the two body members 10 and 11 are assembled, the terminal portion 15a of the stem 15, projects a short distance beyond the outer end of the body member 10, as may be clearly seen in Figure 2 of the drawing, and constitutes an anchorage element. In order to insure that the two members 10 and 11, when telescoped together, may be rotated as a unit for winding a strand of hair therearound, the portion of the stem 15, immediately adjacent its connection to the member 11, is formed with an enlargement, 15b, of polygonal cross section, herein shown as square. The opening 16 of the other body member 10, at its inner end, terminates in a socket 16b, corresponding generally in form and size to said enlargement 15b of said stem 15. Thus, when the members 10 and 11 are telescoped together, said enlargement 15b of the stem 15 and the socket 16b are caused to be interengaged and serve to key said members 10 and 11, together so that they may be positively rotated together as a unit. To facilitate rotating said body A, as a unit, the outer end portion of member 11, adjacent said head 14, is formed with serrated or roughened portions 11a to constitute convenient finger gripping surfaces.

In order to retain the strand of hair in curled or wound formation around the body A of the curler, any suitable form of retaining means may be employed, and as herein shown said retaining means is in the form of an elongated strap 17, preferably of resilient material, such as rubber, having one end formed with an opening 18 adapted to be force fitted over the under-cut head 14 on the body member 11, so as to constitute a disengageable but secure connection of the retaining member to said body member 11. When the two detachably connectible members 10 and 11 are assembled and a strand of hair is wound around the body A, the retaining member 17 is stretched over the curled strand of hair on the body and the anchoring opening 19 of the strap is drawn over and seated on the terminal portion 15a of the stem 15 of the body member 11, as clearly seen in Figure 2 of the drawing. The portion of the strap 17, beyond the opening 19, as indicated at 20, constitutes a finger grip por-

tion to facilitate the removal of the retaining member from retaining relation.

In order to facilitate the initial gripping of the strand of hair, preparatory to winding around the body A, I provide an elongated clip 24, of yoke formation at one end, comprising a pair of arms 25, the outer ends of which are provided with a pair of inwardly projecting nubbins 26, adapted to be spring pressed into a pair of diametrically oppositely located recesses 28, formed in the outer end of the body member 10, so that the clip member 24 becomes hingedly connected to said body member 10. The clip member 24 may be understood to be of conventional form and is of arcuate formation in cross section so as to conform somewhat to the curved contour of the body A. Said clip has the main portion of its length provided with a plurality of apertures 29, the purpose of which is to permit the passage of moisture or liquid therethrough into contact with the portion of the strand of hair embraced between the clip and the body A in the process of operating on a strand of hair to produce a curl.

In using the curler embodying the present invention it is first assembled, as seen in Figure 1 of the drawing, and positioned with respect to the strand of hair to be curled so that the end portions of said strand of hair are gripped between the clip member 24 and the body A. The strand of hair is then curled around the body and clip, and the retaining member 17 is then placed in retaining relation, extending over the curl of hair and attached to the body A, in the manner as represented in Figure 2 of the drawing, in which position the strand of hair curled around the body and clip will be securely retained in curled formation on said body. The strand of hair may be subject to proper liquid treatment, either before or after winding on the body, to facilitate curling and/or setting. After the curl acquires a relatively set formation, the curler may be quickly and easily removed by disengaging the retaining member 17 from the terminal end portion 15a of the stem of the body member 11 and the two body members 10 and 11 then may be axially separated so as to permit the curl to remain, without deformation or alteration in the form and size that it assumed when wound on the curler body. Thus, by the use of my improved curler, it is possible to obtain finished curls of greatly increased permanency of form by eliminating the heretofore necessary practice of unwinding the curled strand of hair from the curler in order to effect removal of the curler therefrom.

While the curler embodying the present invention has great utility for individual or personal use, it also has great utility for use by beauty parlor operators in the process of permanent waving of hair, either by what is known as the heat process or "cold" wave process. By forming the apertures 29 in the clip member, it is possible in the application of various liquids or solutions to the curl of hair to insure that a portion of the liquid or solution comes into contact with the portion of the strand of hair clipped between the clip and the body member.

It is to be understood that the body members 10 and 11 may be composed of any suitable material, such as plastic, metal, wood or various other compositions, and it will be apparent that various forms of detachable connections of the two members constituting the main body may be employed. For example, the stem 15 of member 11, may be so dimensioned and the hole 16

of the body member 10, be so co-related so as to provide an enclosed telescopic connection of the two members, and wherein a suitable nubbin may be formed as an integral part of the outer end of the body member 11, to be engaged by the free apertured end of the retaining strap 17. In lieu of the connection of the body members 10 and 11, as shown, said members may be screw threaded together.

One important advantage of the particular construction herein shown resides in the fact that the two body members 10 and 11 may be quickly and easily separated without the necessity of first manually disengaging the retaining member 17. It will be apparent that as the body members 10 and 11 are engaged at opposite ends and are pulled in a direction to separate them axially, the terminal extension portion 15a of the stem 15 becomes disengaged from the aperture 19 of the retaining strap 17, and releases the strap, thus making the matter of removing the curler from the curl of hair quick and easy, requiring a minimum amount of time, while at the same time resulting in a finished curl of substantially the same size as initially formed when wound around the body of the curler, and which curl, due to the avoidance of unwinding, as has heretofore been the practice by the use of prior curlers, results in greater permanency of formation of the curl. Furthermore, the construction is such that if desired, after disengagements the retaining strap 17, only one of the members constituting the main body of the curler, may be removed from within the curl, and the other member, and preferably the member 10 carrying the clip 24, may be rotated in a direction to unwind the curl so as to produce a curl of a desired size.

While, as above stated, the novel curler embodying the present invention is adapted for use by individuals personally, or by beauty parlor operators for producing curls, it is of especial advantage for use in forming curls by what is known as a "cold" permanent waving process. In order to obtain a better understanding of the advantages resulting from such use of my novel curler, a comparison will now be made in carrying out the process of "cold" permanent waving by the use of curlers of the type heretofore available and by the curler embodying the present invention.

Up to a certain point in the process the steps are the same in the use of both the prior type of curler and the curler embodying the present invention. In producing a "cold" type of permanent wave a suitable curling solution is applied to the hair, either before or after the hair is wrapped around the curler. The purpose of this solution is to condition the hair and assist in forming curls. The strand of moistened hair wound around the curler, is permitted to remain in such curled condition for a period of time, after which rinsing water is applied to the strand of hair wound on the curler. Then a suitable neutralizing solution is applied to the strand of hair wound on the curler, the purpose of which is to chemically offset or neutralize the curling chemical first employed and to assist in setting or making permanent the hair in the curled or wound form. Up to this point in the process the practice in the use of conventional heretofore available curlers and the curler embodying the present invention are substantially identical.

When using prior conventional curlers, the next step in the process consists in unwinding the

5 strand of hair in order to remove the curler, which tends to destroy the curled formation of hair as existed on the curler. The strand of hair in this condition assumes a semi-straight or flattened wavy form, at which time a second neutralizing solution is applied, and the strand of hair is fingered to again impart a curled formation thereto. By virtue of such steps the strand of hair tends to become set before the hair is in 10 complete curled formation. The curls are then rinsed and dried. By virtue of these steps the curls produced definitely lack permanency and the necessary tendency to retain shape and size.

15 The subsequent steps of the "cold" waving process when using the curler embodying the present invention, consists in removing the two piece curler construction from the wound curl in the manner heretofore described, leaving the wound curl of hair in substantially the same shape and size as assumed when wound on the curler. A second application of neutralizing solution is made to the curl in this form, which tends to permanently set the curl in true curl formation. After setting of the curls they may be rinsed and dried. Such steps result in producing a curl of great permanency, resiliency and a tendency to retain and assume the position, size and conformation assumed when initially wound on the curler. These same advantages are also attained when the curl is enlarged by 20 partial unwinding as above described.

25 Another advantage resulting from the use of the curler embodying applicant's invention, in the application of the "cold" permanent waving process, is in the formation of so-called "pin" curls. After removal of the two piece curler device the curled strand of hair is grasped by the fingers to 30 reposition it with respect to the head in a desired manner and location, and the curl may be affixed in such position with hair pins or the like. In this fixed position the curl is then subjected to a second application of neutralizing solution so as to set the "pin" curl, relatively permanently, in the size, shape and position then assumed. The "pin" curls may then be rinsed and dried. This process of forming "pin" curls is not possible when using conventional, heretofore available types of curlers.

35 It will be apparent that if the hair is set in "pin" 40 curls and neutralized in that position, it accomplishes two main objectives; one it makes finger waving unnecessary, and two, if the hair is subsequently dried without first resetting, it will be found to have far less relaxation at a later time.

45 50 Although I have herein shown and described a preferred embodiment of my invention, manifestly it is capable of various modifications and rearrangement of parts without departing from the spirit and scope thereof. I do not, therefore, wish to be understood as limiting this invention to the precise embodiments herein disclosed, except as I may be so limited by the appended claims.

55 I claim as my invention:

60 65 1. A hair curler of the character described, comprising an elongated body formed of two separate members adapted to be detachably connected together in axial relation, one of said members having an axial bore extending the entire length thereof, the other member having a stem adapted to be telescoped through said bore of said one member, when the members are assembled in operable relation, with the terminal end of said stem projecting a short distance beyond the outer end of said one member, and an

elongated strap of yieldable material connected at one end to the outer end of said other member and detachably connectible to said terminal end of said other member, when said members are operably connected together for releasably maintaining said members in such connected relation.

2. A hair curler of the character described, comprising an elongated body formed of two separate members adapted to be detachably connected together in axial relation, one of said members having an axial bore extending the entire length thereof, the other member having an elongated stem at one end thereof adapted to be telescoped through said bore of said one member

when the members are assembled in operable relation with the terminal end of said stem projecting a short distance beyond the outer end of said one member, said stem and bore having co-operating features adapted to be engaged when said members are axially assembled for keying said members together for rotation as a unit, and an elongated strap of yieldable material connected at one end to the outer end of said other member and detachably connectible to said terminal end of said other member, when said members are operably connected together, for releasably maintaining said members in such connected relation.

JACK ASHFORD.
